Primary Examiner — Cynthia Ramirez(74) *Attorney, Agent, or Firm* — Heslin Rothenberg Farley & Mesiti, P.C.**CLAIM**

The ornamental design for a refuse container, as shown and described.

DESCRIPTION

FIG. 1 is a front-top-right perspective view of a refuse container showing my new design;

FIG. 2 is a front elevational view thereof;

FIG. 3 is a rear elevational view thereof;

FIG. 4 is a right side elevational view thereof;

FIG. 5 is a top plan elevational view thereof;

FIG. 6 is a front-top-right perspective view of an alternate embodiment of a refuse container showing my new design;

FIG. 7 is a front elevational view thereof;

FIG. 8 is a right side elevational view thereof; and,

FIG. 9 is a top plan elevational view thereof.

The broken lines shown in the figures are included for the purpose of illustrating portions of the refuse container and form no part of the claimed design.
